CLAIM

The ornamental design for a hexagonal game piece holder with rolling tray, as shown and described.

DESCRIPTION

FIG. 1 is an isometric view of a hexagonal game piece holder with rolling tray.

FIG. 2 is a top view of a hexagonal game piece holder with rolling tray.

FIG. 3 is a bottom view of a hexagonal game piece holder with rolling tray.

FIG. 4 is a right-side view of a hexagonal game piece holder with rolling tray. The left-side view, which is omitted from the figures, is a mirror image of the right-side view; and, FIG. 5 is a side view of the hexagonal game piece holder with rolling tray that is rotated 30 degrees with respect to the view in FIG. 4.

In the drawings, the broken lines depict portions of the hexagonal game piece holder with rolling tray that form no part of the claimed design.

The hexagonal game piece holder with rolling tray may be used on a tabletop or other surface to hold game cards, playing cards, and/or similar objects, and/or roll dice.
